UNITED STATES PATENT OFFICE.

HENRY FURSTE, OF CINCINNATI, OHIO, ASSIGNOR TO THE BOYDELL BROS. WHITE LEAD & COLOR CO., OF DETROIT, MICHIGAN.

DESIGN FOR A LABEL-BLANK.

40,959.

Specification for Design.

Patented Nov. 1, 1910.

Application filed May 20, 1910. Serial No. 562,561. Term of patent 14 years.

To all whom it may concern:

Be it known that I, HENRY FURSTE, a citizen of the United States, residing at Cincinnati, in the county of Hamilton and State of Ohio, have invented a new, original, and ornamental Design for Label-Blanks, of which the following is a specification, reference being had to the accompanying drawing, forming part thereof.

The figure is a plan view of a label blank showing my new design.

I claim:
The ornamental design for a label blank, as shown.

HENRY FURSTE.
